Patented Apr. 7, 1959

184,838

BASEBALL EQUIPMENT CART

Roderick C. Tucker, Scio, N.Y.

Application May 19, 1958, Serial No. 50,968

Term of patent 14 years

(Cl. D14—3)

Fig. 1 is a front elevation of a baseball equipment cart, showing my new design thereof, the same being shown in closed position;

Fig. 2 is a front elevation thereof in open position;

Fig. 3 is a top plan view thereof;

Fig. 4 is a side elevation view thereof;

Fig. 5 is a rear elevation view thereof; and

Fig. 6 is a bottom plan view thereof.

I claim:

The ornamental design for a baseball equipment cart, substantially as shown.
